SIDE FRAME

Mark H. Martin, Reading, Pa., assignor to Birdsboro Steel Foundry & Machine Company, Birdsboro, Pa., a corporation of Pennsylvania

Application January 27, 1932, Serial No. 589,071

7 Claims. (Cl. 105—205)

My invention relates to side frames and pertains more particularly to the type of frame disclosed in United States Letters Patent to Kiesel, No. 1,480,727.

One object of my invention is to provide a side frame of the character indicated which is greatly strengthened over standard practice and in which the deflection between the bolster columns under the increased loading now being generally adopted is reduced to a minimum.

A further object is the provision of a side frame which is arranged for the reception of spring groupings in excess of the standard A. R. A. nest of four springs and to effectively carry the load imposed thereon, the frame being strengthened in critical localities by a novel disposition of strengthening webs or ribs whose precise dispositions are dependent upon the form of spring grouping.

20 A further object is to devise a side frame in which the tension member approximates the form of a catenary in order to provide maximum strength with a minimum waste of metal through a shortening of the linear dimension of the member, the member being further strengthened in order to effectively carry loadings that may be imposed thereon in excess of those normally transmitted by the standard nest of four helical springs.

25 These and further objects of my invention will be set forth in the following specification, reference being had to the accompanying drawing, and the novel means by which said objects are effectuated will be definitely pointed out in the claims.

In the drawing:

Figure 1 is a side elevation of my improved side frame, partly in section, including one end of an associated bolster and a diagrammatic representation of a spring group comprising seven springs.

Fig. 2 is a section along the line 2—2 in Fig. 1, looking in the direction of the arrows, and showing the general arrangement of a suggested form of spring grouping and the latter's relation to the widened portion of the spring seat portion of the frame.

Fig. 3 is a section along the line 3—3 in Fig. 1, looking in the direction of the arrows, the bolster, spring plank and spring grouping being indicated in dotted outline.

Figs. 4, 5, and 6 are sections along the lines 4—4, 5—5, and 6—6, respectively, looking in the direction of the arrows, and illustrating certain

transverse sections taken at the indicated portions of the frame.

Referring to the drawing, the numeral 10 designates the side frame which is provided with the usual compression member 11 and tension member 12 which are formed as parts of a single casting and integral journal boxes 13 are provided at the ends of the frame. Bolster columns 14 extend between said members to define a window opening 15 and said columns define with the spaced portions of the compression and tension members, triangular openings 16. Preferably, the compression member 11 is formed as a channel section which opens downwardly, as indicated in Fig. 5, while the bolster columns 14 are likewise formed as channel sections, as indicated in Fig. 2, which face outwardly toward the openings 16.

The tension member 12 comprises a web which depends from the ends of the compression member 11 and which approaches in length and shape the desired catenary curve, the diagonal portions of said web being indicated by the numeral 17 and the horizontal portion by the numeral 18, the latter forming the spring seat portion of the side frame. As indicated in Fig. 2, the horizontal web portion 18 is laterally widened to provide shelves 19 in order to adequately support the inner and outer groups of springs of a nest which, in the arrangement being described, comprises a total of seven springs, the inner and outer groups each comprising two springs and the intermediate group three springs as shown.

In accordance with standard practice, this spring nest may be rested on a spring plate 21 which is in turn carried by one end of a spring plank 22 that is supported directly by the spring seat portion of the frame, that is, the horizontal web 18 and shelves 19. One end of a truck bolster 23 has sliding engagement with the bolster columns 14 and rests on the upper end of the spring nest 20.

The diagonal webs 17 are provided with upstanding side walls 24 which define the channel section shown in Fig. 4, while the horizontal web 18 is provided with the downwardly extending side walls 25 which define the channel section illustrated in Fig. 6, the lower edges of said side walls being provided with the reentrant flanges 26. The ends of the side walls 25 are tapered as at 27 and merge gradually into the diagonal portions of the tension member 12. As a means of providing additional strength in that portion of the side frame below the bolster opening, the reentrant flanges 26 may be connected by a horizontal web 28 intermediate the ends of the side

walls 25. Gusset webs 29 project laterally from the side walls 25 and provide reenforcement for the underside of the shelves 19, while between the side walls 25, additional gusset webs 30 may 5 be provided to further strengthen the horizontal web 18, the vertical axial planes of the inner and outer springs being common with the vertical planes through the webs 29 and 30.

One of the principal features of the present invention resides in the adoption of devices for sufficiently strengthening that portion of the side frame beneath the bolster opening in order to adequately support the increased loading that would be transferred by a spring nest of the character indicated and these means are preferably in the form of ribs 31 which are integrally formed with the side walls 25 and which face inwardly toward each other. These ribs preferably extend from the ends of the web 28 upwardly to substantially the junction of the diagonal and horizontal web portions 17 and 18, respectively, the rib 31 being substantially a continuation of the diagonal web 17. Accordingly, the tensile stresses which are created in the lower web 28 are carried directly through the ribs 31 to the web 17 without dependence entirely on the side walls 25, thereby greatly increasing the strength and stiffness of the spring seat portion of the frame.

In the frame of the foregoing construction, the web of the tension member 12, including the diagonal and horizontal portions 17 and 18, respectively, is located in positions that conform most naturally to the conditions imposed by the applied load and which resist most effectively the resulting stresses. Since the line connecting the neutral axes of the sections is relatively close to the theoretical line of least bending strain in the tension member, distorting possibilities are reduced to a minimum, so that the member may be formed with less metal without sacrifice of strength than is possible in constructions where the webs of the diagonal members join the bottom webs of the box sections comprising the bottom tie member of the frame. All of the foregoing improvements have been embodied in a frame which is susceptible of being readily cast in accordance with sound foundry practice.

While I have shown one set of elements and combinations thereof for effectuating my improved side frame, it will be understood that the same is intended for purpose of illustration only and in no wise to restrict the same to the exact forms and structures shown, for many changes may be made therein without departing from the spirit of my invention.

I claim:

1. A side frame having a tension member comprising a horizontal web forming a spring seat portion and diagonal webs joining said horizontal web to the compression member of the frame, all of the webs together forming the principal web element of the tension member, said diagonal webs having upwardly extending flanges and said horizontal web having downwardly extending side flanges, the central portion of said side flanges being connected to form a box section having a horizontal lower web whose ends terminate at points in substantial alignment with the diagonal webs extended, and strengthening means extending from substantially the junction of said horizontal and diagonal webs downwardly to the end of the lower web.

2. A side frame comprising a tension member having a horizontal web forming a spring seat portion and diagonal webs joining said horizontal

web to the compression member of the frame, all of the webs together forming the principal web element of the tension member, said diagonal webs having upwardly extending flanges and said horizontal web having downwardly extending side flanges, the central portion of said side flanges being connected to form a box section having a horizontal lower web whose ends terminate at points in substantial alignment with the diagonal webs extended, and strengthening ribs integral with said downwardly extending flanges extending from substantially the junction of said horizontal and diagonal webs to the ends of the lower web.

3. A side frame having a tension member comprising a horizontal web forming a spring seat portion and diagonal webs extending continuously from said horizontal web and connected to the compression member of the frame, all of said webs together being formed substantially as a catenary, said diagonal webs having upwardly extending flanges and said horizontal web having downwardly extending side flanges, the central portion of said side flanges being connected to form a box section having a horizontal lower web whose ends terminate at points in substantial alignment with the diagonal webs extended, and strengthening means extending from substantially the junction of said horizontal and diagonal webs downwardly to the ends of the lower web.

4. A side frame having a window opening and a tension member having a substantially horizontal web portion defining the bottom of said opening and having continuously formed, diagonal web portions connected to the compression member of the frame, all of said portions together being arranged substantially as a catenary, said horizontal web portion having downwardly extending flanges, the central portions of said side flanges being connected to form a box section having a horizontal lower web whose ends terminate at points in substantial alignment with the diagonal webs extended, and strengthening means extending from substantially the junction of said horizontal and diagonal web portions downwardly below said horizontal web to ends of the lower web.

5. A side frame comprising a tension member having a horizontal web forming a spring seat portion and continuously formed, diagonal webs joining said horizontal web to the compression member of the frame, all of said webs together being arranged substantially as a catenary, said diagonal webs having upwardly extending flanges and said horizontal web having downwardly extending side flanges, the central portion of said side flanges being connected to form a box section having a horizontal lower web whose ends terminate at points in substantial alignment with the diagonal webs extended, and strengthening ribs integral with said downwardly extending flanges extending from substantially the junction of said horizontal and diagonal webs to the ends of the lower web.

6. A side frame having a tension member comprising a horizontal web forming a spring seat portion and diagonal webs joining said horizontal web to the compression member of the frame, all of the webs together forming the principal web element of the tension member, said diagonal webs having upwardly extending flanges and said horizontal web having downwardly extending side flanges, the central portions of said side flanges being connected to form a box section having a horizontal lower web, and strengthening means

- extending from substantially the junction of said horizontal and diagonal webs in alignment with said diagonal webs downwardly to the ends of said lower web. 5
7. The combination of a side frame comprising compression and tension members spaced at intermediate portions thereof by bolster columns leaving a window opening therebetween, said tension member comprising a horizontal web forming a spring seat portion and diagonal webs connected to the compression member of the frame, all of said webs together constituting a continuous element arranged substantially as a catenary, said diagonal webs having upwardly extending flanges and said horizontal web having downwardly extending side flanges, the central portions of said side flanges being connected to form a box section having a horizontal lower web whose ends terminate at points in substantial alignment with the diagonal webs extended, shelves extending laterally from said horizontal web to provide a spring plank seat, gusset webs extending from said shelves downwardly along said side flanges, strengthening means extending from substantially the junction of said horizontal and diagonal webs downwardly to the ends of said lower web, and a nest of truck springs carried by said frame arranged in inner, outer, and intermediate groups, the vertical axial planes of said inner and outer groups being common with the vertical planes through said gusset webs and said intermediate group being disposed over said box section. 10 15 20 25 30 35 40 45 50 55 60 65 70 75 80 85 90 95 100 105 110 115 120 125 130 135 140 145 150
